AIR PUMP FOR ARTIFICIAL RESPIRATION

Hermann Tietze, Lubeck, Germany, assignor to
Otto Heinrich Dräger, Lubeck, GermanyApplication January 12, 1951, Serial No. 205,638
In Germany February 13, 1950

6 Claims. (Cl. 128—30)

1

The present invention relates to an air pump for the use in an apparatus for artificial respiration.

Apparatuses for artificial respiration are known in which an air pump produces alternately positive and negative pressure in the rhythm of human respiration, such as the so-called iron lung. In devices of that sort reciprocating air pumps are used which are driven by means of a crank shaft. Membrane pumps are also known, particularly pumps provided with an unelastic membrane, which have the advantage that a physiologically desirable pause between inhalation and exhalation can be obtained.

The known devices are generally provided with a dome which is put over the head of the patient while the respiration chamber containing the patient's body is opened. In that event, respiration through the dome replaces the artificial respiration by means of the respiration chamber of the iron lung, for the time the chamber has to be open for attending to the patient. The periodic alternations in pressure required for artificial respiration are produced in the dome by the same air pump. In changing from one type of artificial respiration to the other, the air pump is switched from the respiration chamber to the dome. Since the pressure in the dome is always opposite to the pressure in the respiration chamber in which the patient is placed, for instance during inhalation there is a negative pressure in the chamber, but a positive pressure in the dome, respiration is one-half a cycle out of phase when the air pump is switched from chamber to the dome, and the patient is exposed to an extended period of exhalation or inhalation, respectively.

There are further disadvantages in the use of the same air pump for chamber respiration and dome respiration in the known manner. Some types of air pumps can be adjusted so as to render the time period of exhalation longer than the time period of inhalation which is desirable for physiological reasons. In the event an air pump of that type is switched from chamber respiration to dome respiration, the time period for inhalation would become longer than the time period for exhalation, which is unbearable for the patient. This undesirable change can only be corrected by a complicated device.

It is the object of the present invention to avoid the drawbacks of the known air pumps for artificial respiration. In the present invention one side of the air pump is connected to the respiration chamber and the other side of the pump to the dome. In an arrangement of that type it is possible to switch from chamber respiration to

2

dome respiration any time without disturbing the rhythm of respiration of the patient or repeating one period of respiration. This arrangement has also the advantage that no complicated switching devices are required.

In a preferred embodiment of the invention the respiration chamber forms one side of a reciprocating air pump. Preferably the wall of the respiration chamber is movable and functions as a membrane. In a simple embodiment of the present invention a movable wall is arranged in the housing of the apparatus, and the opening connecting the other side of the air pump to the atmosphere is preferably disposed in such manner as to lead to the space enclosed by the dome when the dome is placed on the apparatus.

In this arrangement the pressure on this side of the pump is equal to the atmospheric pressure as long as the dome is not used. However, when the dome is connected to the apparatus, positive and negative pressure opposite to the pressure within the respiration chamber is produced within the dome.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a schematic cross-sectional view of an embodiment of the present invention;

Fig. 2 is a schematic cross-sectional view of the air pump according to a preferred embodiment of the present invention;

Fig. 3 is a schematic cross-sectional view of the embodiment shown in Fig. 2 while respiration is effected in the respiration chamber; and

Fig. 4 is a schematic cross-sectional view of the same embodiment while respiration is effected in the dome only.

In the embodiment shown in Fig. 1 the sides of a double acting air pump 18 are connected by an air-duct 19 to the respiration chamber 12, and by an air-duct 15 to the space enclosed by the dome 17. The piston 4 is moved to and fro by a crank drive 20 rotated by drive means, not shown. In the event that the dome is removed, the left side of the air pump is connected to the atmosphere, while positive and negative pressure is alternately produced in the respiration chamber 12, whereby artificial respiration of the patient is caused.

In the event that the dome 7 is secured to the

respiration chamber 12, opposed pressure alternations are simultaneously produced in the dome and in the respiration chamber.

In the event that the respiration chamber 12 is opened, and cover 2 is removed, pressure alternations are produced in the dome 17 only whereby direct artificial respiration of the patient is caused.

In a preferred embodiment shown in Figs. 2, 3 and 4, the top of the housing 1 of the air pump for artificial respiration is closed by an airtightly attached cover 2 provided with openings 3 which can be airtightly closed for attending to the patient 11. In the housing 1 a movable wall 4 is disposed which serves as a membrane of an air pump as used in bellows. The wall is pivotally supported on a shaft 5 on one side, and connected on the other side to the housing by a flexible connection 6, preferably made of a gummed material. The rod 7 passing through an opening 8 in the bottom plate 9 of the housing 1 is connected to the wall 4, and airtightly separated from the second chamber 14 of the air pump by bellows 10. The patient 11 lies in the respiration chamber 12 on mattress 21 which is placed on the air-permeable support 22, said chamber 12 thus forming one side of the air pump, while his head is protruding out of it. Around neck or chest of the patient, a ring-shaped sealing device 13 is placed, airtightly sealing the respiration chamber 12 against the atmospheric pressure.

The second chamber formed by the wall 4 and the bottom plate 9 is connected to the atmosphere by a passage 15 and the opening 16. As shown in Fig. 2, the opening 16 is arranged in such a manner as to be within the area covered by the dome 17, if the dome is placed on the device.

In the arrangement according to Fig. 3, the body of the patient 11 is exposed to pressure alternations in the respiration chamber 12 whereby artificial respiration is obtained. In the second chamber 14 the pressure remains substantially constant since this chamber is connected to the atmosphere by the passage 15 and the opening 16.

In the event that the dome is placed on the device, alternations are produced within the dome which are opposed to the alternations in pressure in chamber 12 (Fig. 2). When cover 2 is taken off, respiration of the patient is only effected through the dome 17 (Fig. 4).

It is an advantage of the present invention that switching from chamber respiration to dome respiration is very easy and does not require any complicated device. Furthermore, the rhythm of respiration remains constant and an exhalation period follows an inhalation period after switching so that the patient does not feel anything of the switch from chamber respiration to dome respiration.

A further advantage of the present invention is that the physiologically required longer time period of exhalation comparing to inhalation is retained in chamber respiration and dome respiration.

It will be understood that each of the elements described above, or two or more together, may also find a useful application in other types of iron lungs differing from the types described above.

While I have illustrated and described the invention as embodied in an air pump for artificial respiration, I do not intend to be limited to the details shown, since various modifications and

structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desire to secure by Letters Patent is:

15. An apparatus for artificial respiration, comprising in combination, air pump means having a reciprocating movable member causing compression and expansion of air on opposed sides thereof; drive means driving said air pump means; a chamber adapted to airtightly enclose the body of a patient substantially one wall of which is formed by one side of said movable member; a dome removably secured to said chamber and adapted to enclose the head of said patient; and air-duct means adapted to connect the other side of said reciprocating movable member to said dome, whereby opposed pressure alternations are produced in said chamber and said dome, respectively.
20. An apparatus for artificial respiration, comprising in combination, reciprocating air pump means having a reciprocating diaphragm; drive means driving said air pump means; a chamber adapted to airtightly enclose the body of a patient disposed directly adjacent said diaphragm whereby one side of the diaphragm will form a part of the wall of the chamber; a dome removably secured to said chamber and adapted to enclose the head of said patient; and air-duct means adapted to connect the other side of said reciprocating diaphragm to said dome, whereby opposed pressure alternations are produced in said chamber and said dome, respectively.
25. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
30. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
35. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
40. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
45. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
50. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
55. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
60. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
65. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
70. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.
75. An apparatus for artificial respiration, comprising in combination, a housing; a dome removably secured to said housing and adapted to enclose the head of a patient; a partition dividing said housing into a first chamber and a second chamber, said first chamber being adapted to airtightly enclose the body of said patient and said second chamber provided with an air tight connection leading to the space enclosed by said dome; a shaft supported in said housing; a reciprocable member pivotally mounted on said shaft and airtightly disposed in said partition and movable from a position reducing the volume of said first chamber and simultaneously increasing the volume of said second chamber to a position of increasing the volume of said first chamber and simultaneously reducing the volume of said second chamber; and drive means operatively connected to said shaft for moving said reciprocable member to and fro, whereby pressure alternations are produced only in said first chamber when said dome is removed, and whereby pressure alternations opposed to each other are produced in said first chamber on one hand and in said second chamber and in said dome on the other hand when said dome is secured to said housing.

ond chamber, said first chamber being adapted to airtightly enclose the body of said patient and said second chamber provided with an air tight connection leading to the space enclosed by said dome; a removable top on said first chamber; a reciprocable membrane disposed in said partition and being airtightly connected therein so as to form part of the partition separating said chamber, said membrane being movable from a position reducing the volume of said first chamber and simultaneously increasing the volume of said second chamber to a position of increasing the volume of said first chamber and simultaneously reducing the volume of said second chamber; and drive means operatively connected with said membrane for moving said membrane to and fro, whereby pressure alternations are produced only in said first chamber when said dome is removed, and whereby pressure alternations opposed to each other are produced in said first chamber adapted to enclose the body of the patient on one hand and in said second chamber and in said dome adapted to enclose the head of the patient on the other hand when said dome is secured to said housing, and whereby pressure alternations are produced only in said second chamber and said dome when said dome is secured to said housing, and said first chamber is opened.

5. An apparatus for artificial respiration, comprising in combination, a housing adapted to airtightly enclose the body of the patient; a dome removably secured to said housing and adapted to enclose the head of said patient and having an air connection with the housing; an airtight partition wall between said housing and said dome arranged movably between said housing and dome so as to reduce and increase the volumes

5

of said housing and dome, respectively during movement; and means for moving said partition wall to and fro creating thereby pressure alternations within said dome and housing, respectively.

6. An apparatus for inducing artificial respiration comprising, in combination, an airtight housing; a dome removably secured to said housing and adapted to enclose the head of a patient; a partition dividing said housing into a first chamber and a second chamber, said first chamber being adapted to airtightly enclose the body of the patient, said second chamber being provided with an airtight connection leading to the space enclosed by the dome; a reciprocable member disposed in said partition, airtightly connected therein and movable from a position reducing the volume of said first chamber and simultaneously increasing the volume of said second chamber, to a position increasing the volume of said first chamber and simultaneously reducing the volume of said second chamber; and drive means operatively connected to said movable member for moving said member to and fro, whereby pressure alternations opposed to each other are produced in said first chamber on the one hand and in said second chamber and dome on the other hand, when said dome is secured to said housing.
